UNITED STATES PATENT OFFICE.

WILLIAM SHEETS, OF PORTSMOUTH, OHIO.

AUTOMOBILE SEAT.

Application filed August 2, 1926. Serial No. 126,698.

This invention relates to an improvement in automobile seats.

The object of the invention is to eliminate the uncomfortable rubbing of the rider's back against the rigid back portion of the seat whenever riding over rough or uneven roads which cause a compression of the springs in the seat.

Automobile seats are ordinarily built with 10 springs inclosed in the seat portion as well as in the back-rest cooperating therewith, both of these being inclosed and covered by upholstery, but, the seat portion and back-rest are entirely independent of each other, 15 and an uneven movement of the vehicle over the road may cause a compression or expansion of the springs in the seat without affecting or without moving the back-rest, so that as the person riding on the seat is moved up 20 or down by reason of that compression or expansion of the spring therein, his back will be moved over the surface of the back-rest, causing a decidedly unpleasant rubbing action between his back and such back-rest.

25 This invention eliminates that unpleasant rubbing action by connecting the back-rest with the seat portion and mounting the seat portion upon springs inclosed in the casing, so that such seat portion may slide up and 30 down in the casing, and whenever such sliding movement occurs, the back-rest will move therewith without causing a change in relative positions of these parts.

Metal guide plates are provided on the 35 edges of the seat to direct the sliding action thereof and these metal guides fit within the casing which also contains the springs for supporting the seat. The back-rest may be hinged to the seat in order that it may be 40 let down in a lowered position to form a bed with the seat and back-rest.

Suitable connecting rods are also provided for connecting the back-rest with the seat and for holding it in its raised position 45 when not used as a bed.

In the accompanying drawings:

Fig. 1 is a perspective view of the invention partly in section; and

Fig. 2 is a detail perspective view of the 50 same.

The numeral 1 indicates the automobile body within which is arranged a casing 2, preferably of metal, although it might be of any other material, and which is provided with a transverse partition 3. A seat 4 is provided with a base plate 5 having

downturned portions 6 at the outer edges thereof, which downturned portions 6 terminate in outwardly extending lugs 7, and the plate 5 is covered with suitable upholstery 8. Metal guide plates 9 are secured to the outer edges of the lugs 7, as clearly shown in Fig. 2, and these guide plates 9 are adapted to be interposed between the lugs 7 and the metal casing 2 in order to permit 60 of a sliding action between the seat 4 and the casing 2.

The back-rest 10 may be of any suitable form and is hinged to the seat 4 by means of hinges 11 which, as shown in Fig. 2, connect the back 10 with the plate 5 of the seat 4. The purpose of hinging the back 10 to the seat 4 is to permit of its being lowered into a horizontal position to use the whole seat and back as a bed for reclining if desirable. In order to hold the back 10 in its normally raised position, as shown in Fig. 1, it is detachably or adjustably connected with the seat 4 by means of the holder-bars 12, 70 at the opposite ends thereof, which are connected with the back 10 in any suitable manner to provide for such adjustment and regulation.

The back 10 is thus connected with the seat 4 to move therewith as the latter is 85 slidable in the casing 2, and for the purpose of resiliently supporting the seat 4 above the casing 2, suitable springs 13 are interposed between the plate 5 and the partition 3, and similar but shorter springs 14 are 90 interposed between the partition 3 and the lugs 7. These springs normally hold the seat and back in the positions shown in Fig. 1, but whenever the vehicle moves over an uneven place in the road, the springs are caused 95 to expand and contract, sliding the seat 4 in the casing 2, such sliding action being guided and directed by the metal guide plates 9, and by reason of the connection between the seat 4 and the back 10 this back is also moved with the seat, in order to prevent the movement of one relative to the other. The springs 13 and 14 provide a 100 sufficient resilient support for the back and seat to allow comfortable riding thereon.

I claim:

1. A device of the character described including a casing, a seat associated with said casing and having a bottom plate, said plate having downwardly extending and outwardly projecting lugs formed on the edges thereof, guide plates secured to the outer edges 110

of the lugs for guiding the sliding movement of the seat within the casing, springs mounted within the casing for resiliently supporting the seat, and a back fixed to said seat 5 to slide therewith.

2. A device of the character described including a casing, a seat associated with said casing and having a bottom plate, said plate having downwardly extending and outwardly 10 projecting lugs formed on the edges thereof, guide plates secured to the outer edges of the lugs for guiding the sliding movement of the seat within the casing, springs mounted within the casing and engaging the 15 plate and lugs for resiliently supporting the seat, a back pivotally secured to the seat to slide therewith relative to the casing, and means for adjustably holding said seat back in its raised position and to permit the same 20 to be folded down in a substantially horizontal position.

3. A device of the character described including a casing, a seat slidably mounted for substantially vertical movement in the 25 casing, said seat having a bottom plate provided with downwardly extending and outwardly projecting lugs formed on the edges thereof, guide plates interposed between the outer edges of the lugs and casing and carried by the lugs for guiding the sliding 30

movement of the seat, a back rest secured to the seat independently of the casing for vertical movement therewith, a partition mounted in the casing, and supporting springs interposed between the partition and the bottom plate and lugs for resiliently supporting both the seat and back rest. 35

4. A device of the character described including a casing, a seat associated with the casing and having a bottom plate provided with downwardly extending and outwardly projecting lugs formed on the edges thereof, guide plates secured to the outer edges of the lugs for guiding the sliding movement of the seat within the casing, and springs 40 mounted within the casing for resiliently supporting the seat. 45

5. A device of the character described including a casing, a seat associated with the casing and having a bottom plate provided with downwardly extending and outwardly 50 projecting lugs formed on the edges thereof, guide plates secured to the outer edges of the lugs for guiding the sliding movement of the seat within the casing, and springs 55 engaging and supporting the plate and lugs for resiliently supporting the seat.

In testimony whereof I affix my signature.

WILLIAM SHEETS.
